MATERNITY DRESS

Aaron E. Haister, New York, N. Y.

Application October 30, 1935, Serial No. 47,494

3 Claims. (Cl. 2--76)

This invention relates to the broad class of ladies' wearing apparel and has more explicit reference to that particular sub-division thereof which embraces special garments generally known in the trade as maternity dresses.

Classified more specifically, the inventive conception when satisfactorily reduced to practice has to do with a more satisfactory and adjustable girth portion expressly adaptable to a slip on dress of the wrap-around type.

In keeping with a sincere and enthusiastic desire to provide a structure characterized by requisite simplicity and expediency and outstanding in comfort and compensating properties I have, after painstaking and thoughtful effort discovered an ingenious coordination of complementary internal and external fastening means for the waist portion of the garment which is deemed to be more aptly fitted than similar prior art structures and susceptible of appropriately meeting the demands of the user and trade in general.

Outwardly, the improved dress has the guise of a well balanced garment either of the commonplace or highly fashionable mode, the adjustable waist portion being nevertheless variable and capable of progressive regulation without materially changing its ever stylish appearance, a feature not found, it is believed, in my predecessors' maternity wearing apparel.

Stated along structural lines the preferred embodiment of the invention has been found to operate satisfactorily when made to utilize properly mated or matched snap fasteners cooperating with a properly arranged and concealed elastic adjustable compensating and take-up strap.

Other features and advantages will become more readily apparent from the following description and drawings.

In the accompanying pictorial drawings where-like numerals are employed to designate like parts throughout the views:

Figure 1 is a perspective drawing showing what may be described as a conventional maternity dress and depicting the features of the invention in such way as to properly portray the merits and novelty.

Figure 2 is a front view with the dress removed from the wearer, a portion of the front or overlapping panel being broken away to expose the important details therebeneath.

Figure 3 is an enlarged horizontal sectional view taken approximately on the plane of the line 3-3 of Figure 2.

Figure 4 is a fragmentary open or plan view disclosing the associated features which go to

make up the improved gather-proof girth or waist portion.

Figure 5 is a fragmentary drawing in perspective detailing the important compensating or take-up strap.

It is evident that the invention is applicable to all types and varieties of garments of the so-called wrap-around slip on type. In other words it could well be used in connection with ladies' coats or even dresses of the non-maternity or conventional type. At the same time it is more satisfactorily adaptable to a regulation dress of the type illustrated for example in Figures 1 and 2. It is unnecessary to go into detail concerning this dress other than to mention that it is unitarily denoted by the numeral 6, the adjustable girth or waist portion being differentiated by the numeral 7 while the inner or underlying panel of the front or skirt portion is represented at 8 and the overlapping or outer panel at 9. Suitable snap fasteners are employed and these may be of any appropriate form but are preferably of the type which may be sewed or stitched on so that the ones not in use after the adjustment is made, may be readily removed to promote neatness of appearance. There is one row of snap fasteners, these being indicated by the numeral 10 and they are located or arranged in a line around the top of the panel 8. They are arranged at definite distances apart and in practice are generally located one inch from each other. It is observed that these are on the exterior of the waistband. The complementary snap fasteners 11 are on the interior so that they may be properly matched or mated with the snap fasteners 10. There is also a row of these fasteners 11 and they too are spaced one inch apart so that they may be selectively engaged with the snap fasteners 10 according to conditions existing and this accomplished in a manner to substantially guard against unsightly gathering. This standardized or uniform cooperation of snap fasteners is believed to be essential in order to render the garment satisfactorily useful under all circumstances. In other words merely having a single snap fastener 11 on the extension flap of the part 10 would hardly do.

As a matter of fact it will be seen from Figure 3 that the snap fasteners must be extended over a considerable distance, that is arranged in a rather long row so that the parts 8 and 9 when overlapped will come together in neat relationship and no portion thereof will sag or get out of order. These inner and outer rows of snap fasteners 10 and 11 constitute so-called external fastening means notwithstanding the fact that the

fasteners 11 are really on the inside of the garment. I merely describe the fasteners this way so as to distinguish from the totally concealed internal supplementary fastening means. This comprises a keeper eye 12 secured to the edge portion 5 of the skirt section 8. This is in alignment with the fasteners 10. The assemblage also includes the cooperating adjustable strap take-up device 13, as better shown in Figure 5. The anchored 10 end of the strap is securely stitched or otherwise fastened as at 14 to the interior of the back portion of the garment at about the waist line so that it will also cooperate with the snap fasteners. This part comprises an elastic strap 15 of appropriate length having one end portion looped as indicated at 16 through a slideable hook 17, the 15 loop being adjustable by way of a sliding buckle 18. This makes an unusually practical unit to accomplish the result desired. In other words by 20 bringing the section 8 around to the front and engaging the hook 17 with the eye 12 this makes it possible to enable the user to more satisfactorily employ the hands in adjusting or connecting the snap fasteners without further trouble. The 25 main purpose of this unit 13 is however to keep the two overlapping sections under constant yieldable stress so as to cause the waist portion to more or less snugly encompass or embrace the abdomen. This feature together with the snap fasteners 30 absolutely prevents this alignment or unsightly sagging of the parts 8 and 9 with respect to each other. In other words it makes up a nice unit or unitary skirt so to speak. The adjustability of this elastic strap unit 13 is an important 35 feature in that it permits it to be regulated in coincidence with the co-relation of the snap fasteners 10 in relation to the companion snap fasteners 11. In other words a hand adjustment can be made as the girth portion of the garment is 40 progressively increased. Even so, however, the structure does not gird the wearer but on the other hand promotes lasting comfort. It is evident that the elasticity of the strap permits it to possess the requisite compensating expanding and 45 contracting result necessary to accommodate the wearer while standing, bending or reclining as the case may be. Rigid bow tied tapes such as are sometimes employed will obviously not do or take the place of this self-adapting feature.

50 Emphasis and stress is attached to the proper distancing or gauging of the application of the rows of snap fasteners 10 and 11. This is necessarily so to provide proper mating or matching. It promotes precision and uniformity and avoids 55 unsightly gathering as before pointed out. There is obvious continuity and action between the features 12 and 13 and the snap fasteners 10 and 11. In other words these parts operate collectively to provide the desired result based on sound reasoning to insure perfection of fit and accompanying comfort for the wearer. Thus the garment as made with these features is better equipped and aptly fitted to serve the intended purposes with requisite efficiency.

60 It is thought that persons skilled in the art to which the invention relates will be able to obtain a clear understanding of the invention after considering the description in connection with the

drawings. Therefore, a more lengthy description is regarded as unnecessary.

Minor changes in shape, size, and rearrangement of details coming within the field of invention claimed may be resorted to in actual practice, if desired. 5

Having thus described the invention, what is claimed as new is:

1. A maternity dress including a vertically split skirt portion defining an underlying front section 10 and a relatively adjustable overlying companion front section, a hook accommodation and retention eye fixedly secured to the vertical edge portion of the underlying section in alignment with the waist line, a longitudinally adjustable elastic 15 strap rigidly secured at one end to the inner surface of the back portion at the waist line and having a slideable hook engageable with said retention eye, a row of equally spaced snap fasteners secured longitudinally to the outer surface of said 20 underlying front section in alignment with the waist line, and a plurality of correspondingly spaced companion snap fasteners secured at the waist line to the inner surface of the overlapping skirt portion and selectively engageable with the 25 first named snap fastener.

2. In a wrap-around garment including a circumferentially expansible and contractible waist portion and a complementary skirt portion made up of a relatively stationary underlying front section, and a bodily adjustable overlying companion front section, complementary selectively usable separable fasteners attached to the respective front sections in alignment with said waist portion to facilitate and maintain the circumferential adjustment of said waist portion, a keeper eye secured to the free edge of the underlying section in normal alignment with said waist portion, a free handling bodily movable all elastic adjusting and take-up strap solely connected and supported 40 at one end to the inside of the back portion of said garment the free end portion of said strap being formed into a longitudinally extensible and contractible loop, said loop being provided with an adjustable buckle to facilitate lengthening 45 and shortening of the strap as a unit, and a slideable hook carried by said loop and releasably engageable with said eye.

3. A maternity dress including a vertically divided skirt portion defining an underlying front 50 section and a relatively adjustable overlying companion front section, a hook accommodation and anchoring eye fixedly secured to the vertical edge portion of said underlying front section in a position in alignment with the normal waist line of 55 said skirt portion, a longitudinally adjustable horizontally disposable elastic strap rigidly secured at one end to the inner surface of the back portion of said waistline portion having a slideable hook engageable with said eye, a horizontal row 60 of fasteners secured circumferentially to the outer surface of said underlying front section in alignment with said waistline, and a plurality of correspondingly arranged companion separable fasteners secured at the waistline to the inner 65 surface of the overlapping skirt portion and selectively engageable with said first-named fasteners.

AARON E. HALSTER.
